MEANS FOR DELIVERING AN OBJECT TO
A MOVING VEHICLEGeorge G. Glenn, Maywood, Calif., assignor
to A. F. Glenn

Application December 13, 1945, Serial No. 634,841

3 Claims. (Cl. 258—2)

1

This invention relates to a message delivery device adapted to be held by a station agent or other person standing beside a railroad track for delivering a message to the engineer, crewman or conductor on a moving train.

More specifically, the invention relates to a message delivery device particularly adapted for use at night, or in the dark, and which will enable the message carried thereby to be delivered with a maximum of safety to both the person holding the delivery device and the person on the train who removes the message from the delivery device.

The present message delivery device constitutes an improvement over prior train message delivery devices in that it includes a frame embodying light-transmitting message supporting elements; a light source; and means on said light source for detachably securing said frame to said light source, said message supporting elements being adapted to be rendered luminous by the light from said light source, thus making it possible for the person on the moving train who is to receive the message to not only clearly see the message that is to be picked up in the darkness, but to also clearly see the outline of the message carrying frame itself, so that the hand or arm of said person will not be injured by inadvertent impact against the message delivery device during the act of removing the message therefrom while the train is rapidly moving past said device.

Accordingly, the principal object of the invention is to provide a message delivery device including a message carrying frame that can be clearly seen in the dark, and which will thereby provide a maximum degree of safety for both the person holding the message delivery device and the person on the rapidly moving train who removes the message from said message delivery device.

Another object of the invention is to provide a light-transmitting message carrying frame adapted to be rendered luminous by any conventional or suitable light source, such as a conventional flashlight or brakeman's electric lantern.

Another object of the invention is to provide a luminous message supporting frame that can be readily detached from its associated light source after the message carried by said frame has been delivered to, say, the engineer, in order to permit a similar message supporting frame to be quickly substituted therefor for delivering a second message to, say, a brakeman, on the same train.

Another object of the invention is to provide a message supporting frame and means for detachably securing the same to a light source arranged so that said light source can be used for its normal intended functions when said message supporting frame is detached therefrom.

A further object of the invention is to provide a message delivery device from which the message can be removed with deliberate certainty in

2

the dark by a person on a moving train, thereby eliminating the waste of time incident to stopping of the train and backing up to pick up a missed message, and which waste of time occurs quite often with prior message delivery devices due to the failure of persons on moving trains to clearly see such message delivery devices.

A still further object of the invention is to provide a message delivery device that is light in weight, extremely simple in construction, and relatively inexpensive to manufacture.

Other objects and advantages of the invention will be apparent from the following description taken in conjunction with the accompanying drawings, in which:

Fig. 1 is a front elevational view of a message delivery device including a message carrying or supporting frame embodying the principles of the present invention illustrated in association with a conventional flashlight modified slightly to enable it to illuminate and serve as a support for said frame;

Fig. 2 is an enlarged fragmentary view, partly in section, of the device shown in Fig. 1;

Fig. 3 is an enlarged side elevational view of the message carrying or supporting frame shown in Fig. 1;

Fig. 4 is a transverse sectional view taken on the line 4—4 of Fig. 2;

Fig. 5 is an elevational view of a conventional electric brakeman's lantern modified slightly to enable it to support and illuminate the present message supporting frame; and

Figs. 6, 7 and 8 illustrate a modified message supporting frame and certain stages in the fabrication thereof.

Referring now to Figs. 1 to 4, inclusive, the present message delivery device comprises a message carrying frame 1, and any suitable light source such as a conventional flashlight 2 adapted to serve as a support for said frame. As will be apparent from Fig. 2, the flashlight 2 includes a casing portion 3 provided with threads 4. A concave reflector 5 is disposed within the casing 3 in surrounding relation to a conventional flashlight bulb 6. The conventional flashlight 2 is modified for the purposes of the present invention only to the extent that the usual glass lens (not shown) for the reflector 5 is omitted and an aluminum holder or socket 7 substituted in lieu thereof.

The holder 7 is disposed in concentric relation to the bulb 6 and includes a tubular or cylindrical portion 8 having an annular flange 9 at its lower end extending laterally therefrom. The reflector 5 has a peripheral lip 5^a whose lower surface engages the upper edge 10 of the casing portion 3, and the flange 9 of the holder or socket 7 rests upon the upper surface of said lip. An annular, threaded sheet metal cap member 11 (normally employed to hold the usual glass lens in place) is arranged to engage the upper surface of the

flange 8 to clamp it against the lip 5^a of the reflector 5 to maintain both the reflector 5 and the holder 7 in assembled relation with the flashlight 2. The flashlight 2 also includes batteries (not shown) and a conventional switch 12 for controlling the supply of current to the bulb 6.

The message carrying frame 1 is constructed so that it can be quickly and easily attached to, and detached from, the holder or socket 7. Thus, the message carrying frame 1 includes a cylindrical sleeve in the form of a short length of aluminum tubing 13 of such diameter that it has a close, sliding fit in the cylindrical portion 8 of the holder 7. Arms or rods 14 and 15 have the lower end thereof arranged parallel and disposed within the sleeve 13 with the extremities thereof preferably terminating short of the lower end of said sleeve. The arms 14 and 15 diverge above the tubular sleeve 13 on radii about 45 degrees, as best illustrated in Fig. 1. The arms 14 and 15 are made of a material that will transmit light waves longitudinally thereof and diffuse some light laterally and, hence, can readily be rendered luminous so that they will be clearly visible in the dark. There are commercially available and well known plastic or non-metallic materials that have been found to be highly satisfactory for the purposes of the present invention.

In one operative form of the invention, the sleeve 13 is about four inches long and has an internal diameter of three-fourths of an inch and the arms 14 and 15 are made of solid, clear or colorless rods about twenty inches long and one-half inch in diameter. At least the lower end portions of the arms or rods 14 and 15 are heated in water to soften the same and are then subjected to transverse pressure to alter the same from their true cylindrical cross-section to a somewhat oval cross-section in order to be snugly received within the sleeve member 13, as shown in Fig. 4. The plastic arms 14 and 15 are also bent while in the heated condition so that when they cool they take a permanent set and diverge on an angle of about 45 degrees and jointly simulate the letter Y.

The lower ends of the arms 14 and 15 normally fit tightly within the sleeve 13. However, the arms 14 and 15 are positively retained in assembled relation with the sleeve 13 by a bolt 16 which extends diametrically through said sleeve and through an opening 17 partly formed in the adjacent faces of each of the arms 14 and 15. The bolt 16 is further utilized to secure a pair of resilient clasp elements 18 to diametrically opposed sides of the sleeve 13, the bolt 16 passing through the clasp elements 18, through the sleeve 13, and through the opening 17 formed in the adjacent faces of the arms 14 and 15, as best shown in Fig. 4. A nut 19, threaded upon the bolt 16, retains the parts in assembled relation.

Each of the arms 14 and 15 is provided with a notch 20 at its upper extremity adapted to receive a portion of a cord 21 therein. The cord 21, in use, is fashioned into a loop or endless band having the general shape of an inverted triangle with the sides thereof substantially conforming to the V-shape assumed by the portions of the arms 14 and 15 above the sleeve 13. The triangular loop 21 includes a base portion 22 bridging the gap between the spaced outer ends of the arms 14 and 15 and to which portion a paper 23 having a message written or printed thereon is secured in any suitable manner. The loop 21 further includes a portion 24 at its apex which is adapted to be slipped under the upper end of one

of the clasp elements 18 for detachably retaining said loop upon the frame 1.

When a message 23 is to be delivered to a person on an approaching train, the message is secured to the loop 21 and the loop is mounted upon the frame 1 in the relation above described. The sleeve 13 is inserted into the holder 7 to the depth permitted by the engagement of the lower ends 25 of the clasps 18 with the upper edge of the cylindrical portion 8 of said holder, as shown in Fig. 2. The lower end of the sleeve 13 may be beveled as indicated at 26 to facilitate such insertion. Also, the switch 12 may be actuated to light the bulb 6 to aid mounting of the sleeve 13 in the holder 7, particularly in the dark. The mounting of the frame 1 upon the flashlight 2 thus positions the lower end faces of the arms 14 and 15 in confronting relation to the bulb 6. Hence, when the bulb 6 is lit, light will be transmitted longitudinally through the arms 14 and 15 causing them to become luminous and to "glow" with a whitish light. The arms 14 and 15 thus provide a luminous V above the sleeve 13 visible for a considerable distance in the dark.

In actual use, the agent or person delivering the message holds the message delivery device up and assumes a position beside the track sufficiently close to enable the person on the train who is to receive the message to extend his arm so that his hand will pass between the arms 14 and 15 providing the luminous V, with the result that the loop 21 and its attached message 23 can thus be removed from the frame 1 with deliberate certainty. The luminous character of the arms 14 and 15 makes it possible for the person receiving the message to so coordinate and time the movements of his hand and arm as to avoid impact with the message delivery device. This constitutes an important safety feature over prior message delivery devices inasmuch as it has not been uncommon heretofore for brakemen to seriously injure a hand by striking it against such device in attempting to remove a message therefrom, and, in fact, in some instances the hand of the brakeman has missed the message delivery device altogether and struck the person holding the device, thereby causing serious injury to both persons.

It will be understood that more than one message may be attached to the loop 21, or if separate messages are to be delivered to the engineer at the front of the train and the brakeman at the rear of the same train, the messages may be respectively tied to different loops and mounted upon separate message supporting frames 1, and these frames inserted in succession in the holder or socket 7, the sliding fit between the sleeve 13 and said holder or socket making it possible to readily detach one frame after the loop and message have been removed therefrom and to quickly attach a second frame carrying another loop and message.

Fig. 5 illustrates a conventional form of brakeman's lantern 30 including a plain lamp bulb 31 and a two-way switch 32. The lantern 30 is modified to the extent that a holder or socket 7^a is mounted upon one end thereof in any suitable manner in concentric relation with the lamp bulb 31. The holder 7^a is adapted to slidably receive the tubular sleeve 13 of the message supporting frame 1, in the same manner as the holder 7. A second bulb 31^a, which is usually red, is shown disposed in its normal position and is illuminated in accordance with the direction of actuation of the two-way switch 32.

Fig. 8 illustrates a message supporting frame 33 which is of even simpler construction than that shown in Figs. 1 to 4. Thus, instead of using the two small bars 14 and 15, a single, solid bar 34 (Figs. 6 and 7) of "Lucite" or any other suitable material, is employed. The bar 34 has such external diameter ($\frac{3}{4}$ "') as to snugly fit into a cylindrical sleeve 35 (Fig. 8) similar to the cylindrical sleeve 13. In fabricating the message supporting frame 33, the upper end of the bar 34 is first provided with a transverse notch 36 extending completely across the end face thereof (as shown in Fig. 6). A thin slot 37 (Fig. 7) is next cut into the bar 34 from the notched end thereof in a plane perpendicular to the notch 36. The slot 37 terminates at a point 38 spaced about four inches from the lower end of said bar to provide arms 39 and 40. The edges of the arms 39 and 40 bordering the slot 37 are preferably rounded or smoothed to remove all sharp corners. At least the lower portion of the bar 34 is then heated in water to soften the same and the arms 39 and 40 are spread apart so that they diverge on an angle of about 45 degrees. Upon cooling of the bar 34, the same assumes a permanent Y shape, as shown in Fig. 8. The sleeve 35 and at least one clasp 18^a are then secured to the lower end of the bar 34 by a bolt 19^a.

It will be understood that the message carrying loop 21 can be extended through the notches 36 in the arms 39 and 40 and a portion thereof inserted under the upper end of the clasp 18^a to support a message in a manner similar to that described in connection with the supporting frame 1 shown in Fig. 1. It will also be understood that the sleeve 35 is adapted to be received in either the holder 7 or the holder 7^a in the same manner as the sleeve 13 to mount the frame 33 upon a light source, and that in use the arms 39 and 40 will appear as a luminous V above the sleeve 35.

It will be apparent from the foregoing that when the message supporting frame is detached from either the flashlight 2 or the lantern 30, these light sources may be employed for their normal intended use.

While the present delivery device has been described in connection with the delivery of messages to moving trains, it will be understood that said device is not limited to such use and may be employed for delivering any object, such as a small article; and further, that the delivery may be made to moving vehicles other than trains, such as motor vehicles, boats, etc.

It will be further understood that while a conventional flashlight and brakeman's lantern have been illustrated herein as constituting suitable light sources, the luminous message supporting frame disclosed herein can be used with other suitable types of light sources. However, it is important that the light source not be too strong, otherwise an undesirable glare may result, producing a blinding effect which is incompatible with safety.

It will be further understood that various changes may be made in the details and materials employed in the construction of the message supporting frames 1 and 33, and in the socket or holder means 7 and 7^a for detachably mounting the same upon a light source, without departing from the spirit of the invention or the scope of the annexed claims.

I claim:

1. An object delivery device comprising a pair of members each having the property of transmitting light longitudinally, said members having

diverging portions and coextensive portions, said pair of members comprising a Y-shaped frame in which the diverging portions comprise the arms and the coextensive portions comprise the stem, said latter portions having contiguous faces, a source of light directed to illuminate the end of the stem whereby light is transmitted longitudinally along the stem and along the diverging arms to thereby illuminate the frame, a sleeve receptive of the stem, means extending transversely through the sleeve and in the plane common to the mentioned contiguous faces for securing the frame to the sleeve, said means thereby being disposed other than in the path of light transmitted through the coextensive portions of the stem, a holder for the light source, and means separably connecting said holder and the sleeve.

2. An object delivery device comprising a pair of members each having the property of transmitting light longitudinally, said members having diverging portions and coextensive portions, said pair of members comprising a Y-shaped frame in which the diverging portions comprise the arms and the coextensive portions comprise the stem, said latter portions having contiguous faces, a source of light directed to illuminate the end of the stem whereby light is transmitted longitudinally along the stem and along the diverging arms to thereby illuminate the frame, a sleeve receptive of the stem, means comprising a single bolt extending transversely through the sleeve and in the plane common to the mentioned contiguous faces for securing the frame to the sleeve, said means thereby being disposed other than in the path of light transmitted through the coextensive portions of the stem, a holder for the light source, and means separably connecting said holder and the sleeve.

3. An object delivery device comprising a pair of members each having the property of transmitting light longitudinally, said members having diverging portions and coextensive portions, said pair of members comprising a Y-shaped frame in which the diverging portions comprise the arms and the coextensive portions comprise the stem, said latter portions having contiguous faces, a source of light directed to illuminate the end of the stem whereby light is transmitted longitudinally along the stem and along the diverging arms to thereby illuminate the frame, a sleeve receptive of the stem, a message-carrying loop extending across the diverged end of the arms and having a portion extending to and alongside of the sleeve, a clip for separably engaging said loop portion, means extending transversely through the clip and sleeve and in the plane common to the mentioned contiguous faces for securing the frame and clip to the sleeve, said means thereby being disposed other than in the path of light transmitted to the coextensive portions of the stem, a holder for the light source, and means separably connecting the holder and the sleeve.
